GEORG KORF, OF HAMBURG, GERMANY.

WING FOR FLYING-MACHINES.

1,031,452.

Specification of Letters Patent.

Patented July 2, 1912.

Application filed March 1, 1910. Serial No. 546,719.

To all whom it may concern:

Be it known that I, GEORG KORF, a subject of the German Emperor, and resident of Hamburg, Germany, have invented certain new and useful Improvements in Wings for Flying-Machines, of which the following is a specification.

My invention relates to wings for flying machines, and more particularly to the construction and arrangement of feathers for such wings.

Generally speaking, the wings are made in pairs and are substantial duplicates of each other, the only difference being that in one wing the slope of the various parts is opposite to the slope of the corresponding parts in the opposite wing in the sense that one wing is suitable for the left side of the machine while its mating wing is appropriate for the right side of said machine.

My invention comprehends a wing having a longitudinal tapering member hereinafter designated as a staff made of suitable material more or less resilient, the smaller end of the staff extending to, and in part constituting, the tip of the wing, together with a number of feathers, each having a stem and one or more fins extending from the stem, each fin being of composite structure as hereinafter described and comprising a flexible web.

Reference is made to the accompanying drawings forming a part of this specification and in which like numbers indicate like parts.

Figure 1 is a plan view of a single feather employed more particularly for lifting and provided with a single fin of composite structure; Fig. 2 is a plan view of a feather used more particularly for supporting the weight of the machine when the latter is soaring; Fig. 3 is a plan view of practically the entire left wing of the machine, this wing being provided with separate feathers, each extending directly from it; Figs. 4, 5, 6 and 7 are cross sections upon the lines A—B, of Fig. 2 and are substantially alike with the exception that they show the stem of the feather as constructed of different materials and in different forms.

In the feathers shown in Fig. 1 the stem appears at *a* and tapers in thickness so that its resiliency varies in a ratio related to its thickness. Secured to the stem *a* are a number of ribs *b* extending directly from the stem at various angles, the ribs *b* ad-

jacent to the tip *s* of the stem being more nearly parallel with the stem than are the ribs *b* more remote from the tip. Secured to the ribs *b* is the web *f* made of silk, satin, Chinese tissue paper or any appropriate light fabric permeated with gum or other material whereby it is rendered practically impervious to air. The web *f*, together with the ribs *b* constitute practically a continuous fin extending along almost the full length of the stem. The first rib *b* adjacent to the thicker end of the stem extends from that latter at an angle at about ninety degrees and the other ribs *b* progressively diverge, at smaller angles, approximately to the tip of the feather, as will be understood from Fig. 1.

In the feather shown in Fig. 2, the construction differs from that appearing in Fig. 1 in that, in addition to the fin comprising ribs *b* and the web *f*, I provide another fin made up of ribs *c* and a web *g*, this fin being considerably narrower than the one first described and disposed upon the convex side of the stem *a*, whereas the fin first described is upon the concave stem thereof, the stem being in all instances curved from one of its ends to the other, the greatest curvature being toward the tip, so as to present a concave side and a convex side, as will be seen from Figs. 1 and 2. The cross ribs *b* and *c* are made of any suitable elastic light material having more or less firmness.

According to the form of feather shown in cross section in Fig. 4, the stem *a* is considerably thinner upon its right or convex edge along the line where the web *g* is located. The plane of the stem *a* coincides with the general plane of the cross ribs *f*, *g*, the upper and lower surfaces of the stem sloping relatively to each other and the edge carrying the supporting ribs *g* forming an obtuse angle. I find that this construction practically increases the elasticity of the supporting ribs and also enables the weight of the feather in proportion to the work done by the feather to be greatly reduced. Moreover, additional advantage is gained because of the fact that the feather when in action offers less resistance to the air.

The stems shown respectively at *a'* in Fig. 5, *a''* in Fig. 6 and *a'''* in Fig. 7, while differing in cross section from that shown in Fig. 4, nevertheless embody the same general principles being thinner at the right or upon

the edge carrying the cross ribs *g*. In the feather shown in Fig. 2, the cross ribs *c* diverge at different angles from the stem *a*, the first cross rib of the series at the right 5 according to Fig. 2 making an angle of about ninety degrees with the direction of the stem at that point and the other cross-ribs *c* being successively shorter and making sharper angles toward the tip *s*.

10 An entire wing made of feathers of the kind above described is shown in Fig. 3. The feathers, being mostly of the kind shown in Fig. 2, are so arranged that the narrow fin of one feather slightly overlaps 15 the broad fin of the next successive feather. The feathers are mounted upon the staff *d* and extend from the same at varying angles. The feathers adjacent to the tip of the staff diverge successively at smaller and smaller 20 angles relatively to the staff, and the feathers adjacent to the base or portion of greater diameter of the staff diverge or incline in a direction opposite to that of the feathers nearest the base or thickest portion of the 25 staff *d* which are provided with double fins and are made large whereas the feathers toward the tip are made successively smaller and provided with single fins. The last feather toward the left according to Fig. 3 30 forms practically a continuation of the staff *d*.

The operation of my device is as follows:—The feathers being formed as described are mounted upon the staff and thus 35 formed into a wing. A flying machine is provided with one or more pairs of these wings and is operated in the manner well known in this art. When the machine is in flight, the air pressure upon the underside 40 of the feathers presses the feathers upward and these feathers by virtue of their resiliency tend constantly to return to their normal positions. The feathers are therefore constantly under tension and assume slightly 45 different positions according to the air pressure upon them, which is regulated in a measure by the speed of the machine. Such feathers as, during the flight of the machine, happen to have their stems approximately 50 parallel to the general direction of flight now serve as supporting feathers, their principal office being to sustain the weight of the machine as such weight is sustained in soaring. Further, as the stems *a* diverge from 55 the proximate direction of the general direction of flight, the greater is the measure of usefulness of such feathers for the purpose of carrying the machine forward. The outer feathers therefore which now stand, say at 60 or near an angle of ninety degrees to the general direction of flight serve almost exclusively for purposes of propulsion as distinguished from serving the purposes of sustaining weight. In this connection, it 65 may be noted that around the feathers there

is a column of air tending to counteract the falling of the machine or the downward movement of the wings as the case may be, and the upward pressure of the air column acts differently upon feathers which are 70 disposed at different angles relatively to the direction of flight. For a feather having the general direction of its stem disposed in the proximate direction of the flight of the machine, such feathers tends to bend 75 horizontally whenever the movement of the wing is downward. The feather in question, however, in bending tends to convert the energy due to the bending of the wings into a horizontal forward movement. Another feature, however, which forms a considerable angle to the line of flight when acted upon by the air pressure, constantly has a tendency to propel the machine forward or in other words to exert a power of 80 traction.

The physical actions here to be considered are the following: The column of air formed under the feathers counteracts the weight of the wing or apparatus and curves each 90 single feather upward, that is toward the concave side of the stem; each separate feather is accordingly expanded from bottom to top and tends, corresponding to its elasticity, constantly to contract again. 95 When the feathers lie in the direction of flight, they tend merely to carry weight already lifted by bending horizontally; by the movements of the wings downward, these feathers however would bend higher than 100 horizontally, and therefore must be bent with their lower edges at a pointed angle sloping to the back, and thus convert the vertical movement of the beating of the wings into horizontally forward movements. 105 The fins *f* are comparatively broad, and the breadth of the fins which are at the rear of the direction of flight increase constantly, whereas the breadth of the front fins decrease and the outer top feather at last only 110 possesses a single fin. The air pressure meeting these feathers from below now bends each single feather, in consequence of the resultant of strains upon it, into a horizontal direction, that is, in the direction of flight 115 forward, as illustrated in dotted lines in Figs. 1 and 2, the curving being facilitated by the particular arrangement of the cross section of ribs *a* and *b*. These feathers are therefore extended forwardly in horizontal 120 direction, and constantly try to contract in a horizontal direction backward. In other words, the air pressure which acts by the weight of the machine and its tendency to fall is converted into horizontal traction, 125 and this traction is continuous. By the beating of the wings the feathers adapted for traction are bent forward still farther and are at the same time rotated somewhat relatively to their longitudinal axis, as in 130

this case the air pressure must act still stronger on the one sided fins of the feathers. By the beating of the wings the forward movement is in consequence not only accelerated, but a traction or forward movement is always present even without the beating of the wings, by simple soaring flight in consequence of the horizontal tension of the top feathers. The feathers are constantly endeavoring to expand but are kept thus in tension by the air pressure from below, and as the feathers cannot spring backward, the wing, and with it the flying machine, must follow the tension of the feathers, and thus is propelled forwardly. A contraction of the feathers can only occur when the air pressure no longer acts from below, and this air pressure is present as long as the flying machine has no other support below itself than the air, on which it rests in consequence of its weight.

Having thus described my invention, I claim as new and desire to secure by Letters Patent:

25 1. In a wing for flying machines, the combination of a staff having a gradually decreasing diameter toward one of its ends, and a plurality of feathers mounted upon said staff, each feather comprising a stem, 30 supporting ribs extending from said stem, and a web mounted upon said supporting ribs.

2. In a wing for flying machines, a feather comprising a stem, a plurality of supporting ribs extending therefrom, each rib being 35 of greater diameter adjacent to its point of connection with said stem than at the outer or free end of said supporting rib, and a web of thin material mounted upon said supporting ribs.

3. In a flying machine wing, a feather comprising a stem provided with a plurality of fins extending in opposite directions from said stem, one of said fins being of greater width than the other, each fin comprising a 45 plurality of supporting ribs, and a web mounted upon said supporting ribs.

4. In a wing for flying machines, the combination of a staff, and a plurality of feathers carried by said staff, each feather 50 comprising a stem having a thick edge and a thin edge, a plurality of short supporting ribs extending from said thin edge, a plurality of longer supporting ribs extending from said thick edge, and webs of thin material mounted upon said supporting ribs.

In testimony, that I claim the foregoing as my invention I have signed my name in presence of two subscribing witnesses.

GEORG KORF.
